Fig. 3.

Fig. 4.

Fig. 5

Fig. 6.

Fig. 7.

Fig. 8.

Fig. 9.

FIG. 1 is a side elevational view of one side of a camper, showing my new design when in a collapsed condition;

FIG. 2 is a plan view of the camper as shown in FIG. 1;

FIG. 3 is a side elevational view of the camper as illustrated in FIG. 1 and showing the opposite side thereof;

FIG. 4 is an end elevational view of the front end of the camper as shown in FIG. 1;

FIG. 5 is an end elevational view of the rear end of the camper as shown in FIG. 1;

FIG. 6 is a side elevational view of the camper, showing the same side thereof as illustrated in FIG. 1, and showing my new design in an extended condition;

FIG. 7 is a side elevational view of the opposite side of the camper as shown in FIG. 6;

FIG. 8 is an end elevational view of the front end of the camper as shown in FIG. 6; and

FIG. 9 is an end elevational view of the rear end of the camper as shown in FIG. 6.

I claim:

The ornamental design for a camper, as shown.
